7994

British Patent

Feb. 3rd 1834.

The whole operation in the British Patent and making part of the
same consisting of a description in the way of the said John Ryden how
of his Bridge in and the mode of Building Bridge.

The Bridge to be constructed with double wooden cords between which the posts
are placed coming up to the plate about eight feet apart to serve to
brace and extend from the ends to the center of the bridge. The cords
of a bridge being so far from each other one or two or more arches are formed by the
brace running from post to post not which masonry or made to receive the
tire of car or the rails which turns must equally meet in the middle
of each post the masonry made posts to have sufficient space above for
key of which one is placed in each post above the tie braces (or masonry below
or above) to give the key (key) to tighten the tie braces thus formed into the
shape of arch tight & substantial. The first or lower arch thus formed is
commenced on the center or end post about four or five feet below the cords
and a single arch for each end to end in the center of the bridge.
The first arch of brace is also commenced on end and post immediately
above the first arch of bridge constructed in the form of small masonry
or masonry of four or five cords from post to post about two feet below the plate
and so placed along the whole length of the bridge on the bottom post or
cords which are placed into which two horizontal arches are
placed on plate so as they running from the post across from all
the cords so as to come along this with keys to stiffen & strengthen
the bridge.
